(57) **CLAIM**

The ornamental design for vacuum pump, as shown and described.

DESCRIPTION

1. Vacuum pump
- 1.1: Perspective
- 1.2: Perspective
- 1.3: Perspective
- 1.4: Perspective
- 1.5: Front
- 1.6: Back
- 1.7: Left
- 1.8: Right
- 1.9: Top
- 1.10: Bottom

1 Claim, 10 Drawing Sheets(56)
